UNITED STATES PATENT OFFICE

141,842

DESIGN FOR A COMBINED FAUCET SPRAY AND ESCUTCHEON PLATE

Bertrand N. Trombley, Oak Park, Mich., assignor
to The Murray Corporation of America, Detroit,
Mich., a corporation of Delaware

Application March 21, 1944, Serial No. 112,983

Term of patent 7 years

(Cl. D91—3)

To all whom it may concern:

Be it known that I, Bertrand N. Trombley, a citizen of the United States, residing in Oak Park, in the county of Oakland, State of Michigan, have invented a new, original, and ornamental Design for a Combined Faucet Spray and Escutcheon Plate, of which the following is a specification, reference being had to the accompanying drawing, forming a part thereof, wherein:

The figure is a perspective view of a combined faucet, spray and escutcheon plate showing my new design.

What I claim is:

The ornamental design for a combined faucet spray and escutcheon plate, substantially as shown.

BERTRAND N. TROMBLEY.
